SIDE FRAME STRUCTURE

Filed Aug. 29, 1942

Fig. 1

Technical drawing of a mechanical assembly, labeled Fig. 2. The drawing shows a cross-section of a housing or frame structure. Key components and dimensions labeled include:

- Top horizontal bar: 42, 78, 72, 60°, 48, 66, 52, 60.
- Bottom horizontal bar: 56, 46, 54, 64, 58.
- Vertical support: 70, 66, 62.
- Central circular feature: 54.
- Left side vertical element: 1.

SIDE FRAME STRUCTURE

Robert B. Cottrell, Chicago, Ill., assignor to American Steel Foundries, Chicago, Ill., a corporation of New Jersey

Application August 29, 1942, Serial No. 456,696

4 Claims. (Cl. 188—212)

My invention relates to a novel form of truss type railway truck side frame and a novel brake beam support associated therewith.

In a well-known type of truck and brake arrangement, the brake beams are supported from the side frames by parallel flanges integrally formed or supported on the inboard faces of the frame between which may be received projections on the ends of the beams or on the brake heads associated therewith. I have discovered that under certain conditions an improvement in the working arrangement of such a general type of brake beam may be accomplished by using jaw means on the brake beam for cooperation with a single guiding flange integrally formed or otherwise supported on the inboard faces of the side frames.

A more specific object of my invention is to devise a brake beam support formed as an integral part of a well-known type of truss side frame structure comprising tension and compression members and spaced columns wherein the brake beam guide means may comprise a diagonal bracket or flange formed on the inboard face of each frame adjacent each column thereof, and wherein one end of said bracket or flange may merge with the nearby column at its juncture with the spring seat portion of the side frame and the opposite end thereof may merge with an intermediate portion over a diagonal part of the tension member.

In the drawing,

Figure 1 is a side elevation taken from the inboard face of my novel form of side frame structure with brake beam supports thereon, only one end of the frame structure being shown inasmuch as opposite ends are alike.

Figure 2 is a bottom plan view of the side frame structure shown in Figure 1, and Figures 3 and 4 are sectional views, Figure 3 being taken approximately in the transverse diagonal plane at one extremity of the brake beam supporting bracket as indicated by the line 3—3 of Figure 1, and Figure 4 being taken in a plane parallel to that of Figure 3 and through an intermediate point of said supporting bracket approximately as indicated by the line 4—4 of Figure 1, the associated brake beam being fragmentarily indicated.

My novel side frame structure is of well-known truss type with a top or compression member 34 and a bottom or tension member 36, the integral column 38 forming with said members a central bolster opening 37 and having intermediate bolster guide means 40. The tension and

compression members have diagonal end portions outwardly of the column forming therewith the window opening 44 and merging adjacent their ends with the integral box 42. The column 38 may be of generally U-section with the vertical transverse web 46 (Figure 2) merging at its lower end as at 48 with the diagonal web 50 of the tension member, said web 50 being a continuation of the web 52 affording a spring seat 10 at the bottom of the bolster opening. Beneath said bolster opening 37, the tension member 36 may have a box-section with said top chord 52, the bottom chord 54, the inboard wall 56, and the outboard wall 58, said top chord 52 being widened and formed with lateral upstanding inboard and outboard flanges 60 and 62 defining the before-mentioned spring seat. The spring seat 52 may have a plurality of spring positioning means 64, 64 in usual manner and may be cored away as at 66, 66 to permit escape of surplus water or other extraneous matter.

The bottom chord 54 of the tension member extends into the diagonal portions thereof as best seen in Figures 3 and 4, the tension member outwardly of the the columns being of U-section and comprising an inboard web 68 and an outboard web 70, as well as the before-mentioned transverse web 54.

On the inboard face of the frame and at each end thereof may be formed an integral brake beam guide bracket or flange 72, one extremity of which may merge as at 48 with the web 46 of the column and the web 52 of the tension member, as well as the extension 50 thereof, and 35 at said juncture the top surface of the flange 72 may be cored away as at 74 (Figure 1) for convenient foundry practice. The opposite end of the guide bracket or flange 72 may be similarly cored away on its top surface as at 75 and may 40 be reinforced by the web 76 merging with the side wall 68 of the tension member, and this end of the bracket 72 may be cored away as at 78 to provide additional wheel clearance. It will be understood that the portion of the web 46 inboard the web 68 defines a gusset or reinforcing web to strengthen the connection between the flange 72 and the column, said gusset affording a convenient abutment at the rear extremity of the flange 72 to prevent the beam from sliding off the rear extremity of the flange 72 in the release movement of said beam away from the associated wheel.

An opening 80 or a plurality of them may be cored in the bracket 72 for reception of securing lugs 82, 82 which may be integrally formed with

the spring wear plate or liner 84, said liner conforming in general shape to the configuration of the shelf 72 and extending from one extremity to the other thereof and being receivable within the jaw end portion 86 of the brake beam as illustrated in dotted lines in Figure 4.

It will thus be seen that my improved arrangement the side frame structure is simplified and the brackets formed on the inner face of each side frame afford a simple and effective means of association with the jaw ends of the before-mentioned type of brake beam. It may be noted that with this arrangement there is little tendency for the bracket on the side frame to accumulate extraneous matter which might interfere with the normal sliding operation of the brake beam in its association with the side frame and, particularly, that said normal sliding movement will tend to clear any matter that might thus accumulate.

It should be noted that while the plane of the supporting bracket 72 is approximately radial to the wheel center as indicated at 88 (Figure 1), nevertheless, it may vary slightly with respect thereto in order to afford satisfactory engagement between the shoes on the brake beam and the periphery of the adjacent wheel.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. A truss side frame comprising tension and compression members and a column adjacent each end of the frame merging with said members to define therewith a window opening and a bolster opening, said column having inboard and outboard walls and a transverse web extending therebetween and defining the adjacent margin of said bolster opening, said tension member being of box-section beneath said bolster opening with the top chord of said box-section widened and formed with upstanding inboard and outboard flanges defining a spring seat, said flanges merging with said inboard and outboard walls and with said web adjacent the lower extremity of said column, and a brake beam bracket consisting of a guide web extending from the inboard side of said tension member and being disposed in a plane approximately radial to an associated wheel, and a pair of spaced reinforcing webs connected to said guide web at the forward and rear extremities thereof respectively, one of said spaced webs merging with said transverse web and with said inboard flange and presenting a substantially vertical abutment surface at the rear extremity of said guide web to prevent an associated brake beam from sliding off the rear extremity of said guide web.

2. A truss side frame comprising tension and compression members and a column adjacent each end of the frame merging with said members to define therewith a window opening and a bolster opening, said column having inboard and

outboard walls and a transverse web extending therebetween and defining the adjacent margin of said bolster opening, said tension member being of box-section beneath said bolster opening with the top chord of said box-section widened and formed with upstanding inboard and outboard flanges defining a spring seat, said flanges merging with said inboard and outboard walls and with said web adjacent the lower extremity of said column, and a brake beam bracket consisting of a guide web extending from the inboard side of said tension member, and a pair of spaced gussets connected to said guide web at the forward and rear extremities thereof respectively, one of said gussets merging with said transverse web and with said inboard flange and presenting an abutment surface at the rear extremity of said guide web to prevent an associated brake beam from sliding off said rear extremity.

3. A truss side frame comprising tension and compression members and a column adjacent each end of the frame merging with said members to define therewith a window opening and a bolster opening, said column having inboard and outboard walls and a transverse web extending therebetween and defining the adjacent margin of said bolster opening, said tension member being of box-section beneath said bolster opening with the top chord of said box-section widened and formed with upstanding inboard and outboard flanges defining a spring seat, said flanges merging with said inboard and outboard walls and with said web adjacent the lower extremity of said column, and a brake beam bracket consisting of a guide web extending from the inboard side of said tension member, and a reinforcing web connected to said guide web at the rear extremity thereof and merging with said transverse web and with said inboard flange, said reinforcing web presenting stop means at the rear extremity of said guide web for abutment with an associated brake beam under certain operating conditions.

4. A truss side frame comprising tension and compression members and a column adjacent each end of the frame merging with said members to define therewith a bolster opening, said column having an inboard wall and an angularly related transverse web defining the adjacent margin of said bolster opening, said tension member being of box-section beneath said opening with the top chord of said box-section widened and formed with an upstanding flange defining the inboard margin of a spring seat on said top chord, said flange merging with said wall and with said web adjacent the lower extremity of said column, and a brake beam bracket comprising a guide web extending from the inboard side of said tension member, and a reinforcing web connected to said guide web at the rear extremity thereof, said reinforcing web merging with said transverse web and with said flange, and said reinforcing web presenting stop means at the rear extremity of said guide web for preventing an associated brake beam from sliding off said rear extremity.

ROBERT B. COTTRELL.
